UNITED STATES PATENT OFFICE.

EUGENE L. GREENEWALD, OF WASHINGTON, DISTRICT OF COLUMBIA.

APPARATUS FOR APPLYING CLOSURES.

1,398,963.

Specification of Letters Patent.

Patented Dec. 6, 1921.

Application filed June 30, 1915. Serial No. 37,282.

To all whom it may concern:

Be it known that I, EUGENE L. GREENEWALD, a citizen of the United States, residing at Washington, District of Columbia, 5 have invented certain new and useful Improvements in Apparatus for Applying Closures, of which the following is a specification.

My invention relates to a method and apparatus for closing the ends of tubular bodies and has particular reference to a machine for securing a head or cap to the end of a can or similar article.

The primary object of the invention is to 15 provide a machine for automatically seaming the heads or covers on can-bodies or similar articles by corrugating mechanism so that the seal will be perfect and so that the can will be readily openable without 20 rupturing any of the parts of the can.

A further object is to provide novel means for feeding the can-bodies to the machine and novel means for feeding the caps to the bodies.

25 Another object is to provide a stationary seaming table and novel mechanism for moving the cans to their successive positions on said table.

Another object of the invention resides in 30 the mechanism for placing the caps on the can bodies properly and locating and locking the tongues on the caps.

Another object relates to the molds whereby the top ends of the filled cans are trued 35 or shaped so as to become cylinders.

Another object is to provide a center pad which is heated so as to expel the sealing or soldering material from the groove in the cap provided for holding such material.

40 Another object is to provide mechanism for simultaneously corrugating and bending down the peripheral edge portion of the cap with the flange on the body and also forming a bead or shoulder on said members. The said mechanism may be designed 45 so that only the cover part is corrugated and bent into locking position, or so that a bead is formed on said body only.

The above and other objects and the novel 50 features of the invention will be apparent from the following description taken in connection with the accompanying drawings in which—

55 Figure 1 is a horizontal sectional view of a machine embodying my invention, the see

tion being taken on the line 1—1 of Fig. 9, looking in the direction of the arrows, parts being shown in plan;

Fig. 2 is an enlarged vertical sectional view of part of the machine, taken at the 60 line 2—2 of Fig. 1, looking in the direction of the arrows;

Fig. 2^a is a perspective view of the cap;

Fig. 3 is an enlarged vertical sectional view taken on the line 3—3 of Fig. 4 showing one portion of the mechanism for removing the can head from the magazine and for locating the tongues thereof;

Fig. 4 is enlarged horizontal sectional view of part of the mechanism shown in 70 Fig. 3 and taken on line 4—4 of the latter figure, looking in the direction of the arrows;

Fig. 5 is an enlarged fragmental detail view of a portion of the member for removing the cap from the magazine;

Figs. 6, 7 and 8 are enlarged detail views illustrating the successive positions of the devices which tuck the tongue of the cover under the flange of the body;

Fig. 9 is an enlarged vertical cross-sectional view of the machine taken on the broken line 9—9 of Fig. 1;

Fig. 10 is an enlarged vertical sectional view of the seaming and corrugating mechanism as it appears at the beginning of the seaming operation;

Fig. 11 is a horizontal sectional view taken on the line 11—11 of Fig. 10 illustrating part of the mechanism in plan;

Fig. 12 is a view, partly in section, and partly in side elevation illustrating the mechanism for automatically feeding the cans to the seaming table;

Figs. 13 to 16 inclusive are detail views 95 illustrating in section successive positions of the can parts and corrugating devices during the seaming operation;

Figs. 17, 18 and 19 are detail views illustrating in side elevation successive positions 100 of the can parts and corrugating devices during the seaming operation.

Referring to the drawings, 25 designates a stationary platform which supports the parts of the machine. The platform 25 is substantially circular, and is supported above the floor by the legs 26. The platform 25 has a laterally projecting part 27 at one side which supports the end of the can feeding mechanism and the devices which automatically 110

control the delivery of the cans to the can supporting table 28. The table 28 is stationary and has a flange 281 to receive the bolts 282 by means of which it is rigidly secured 5 to the central supporting standard and bearing 29. The member 29 has a base flange 291 and is mounted on the platform 25 at the center thereof and secured to said platform by bolts 292, which bolts extend through the 10 flange 291, platform 25 and flange 301 of a bearing 30, holding the latter in place against the under side of the platform.

The mechanism for moving the cans C or similar articles along the surface of the table 15 28 comprises a series of pusher arms 31, eight in the present instance, which are arranged radially of the table 28 and secured at their inner ends by bolts 311 to the top side of a wheel 32 which has the radial slots 321 and 20 concave recesses 322 which form part of a Geneva gear mechanism whereby a step by step or intermittent rotation is imparted to the wheel 32 and arms 31 mounted thereon. At the center of the machine, the arms 31 and 25 wheel 32 are provided with oppositely extending flanges 313 and 323 which bear against the table 28 and flange 291 and form a hub therefor whereby the arms and wheel are rotatably mounted on the standard 29.

30 The driving member of the Geneva gear mechanism comprises a roll 33 rotatably mounted on the end of an arm 331 integral with the disk 332 which is mounted on the main vertical drive shaft 34 to rotate therewith. The disk 332 has a part of a peripheral curvature to fit the concave parts 322 of the wheel 32 and has a recessed portion 333 so that it will clear the ends of the portions having the radial slots 321. Each revolution 35 of the shaft 34 and disk 332 serves to rotate the wheel 32 and the arms 31 an eighth of a revolution and during each revolution of the disk 332, the wheel 32 and arms 31 will have a period of movement and a period of rest 40 as is common in this type of mechanism.

Referring to Figs. 9 and 12 it will be seen that the shaft 34 is mounted in the bearings 341 and 342 and is continuously rotated by an electric motor which is connected to the 45 shaft 34 by the gears 343 and 344. A sprocket wheel 35 is mounted on the shaft 34 and is connected by a chain 351 to a sprocket wheel 352 fixed on the lower end of the spindle 36 which is rotatably mounted in 50 the stationary bearing sleeve 37 supported on the extension 27 of the platform 25.

A stationary cam 38 is supported on the upper end of the sleeve 37 and has a peripheral cam surface upon which the roller 39 runs. The roller 39 is mounted on the inner 55 end of an extensible arm 40 slidably mounted in the guides 41, 41 on the under side of the rotatable arm 42 fixed on the spindles 36.

When the spindle 36 rotates the arm 42 rotating therewith, carries the extension 40

thereof around and as the roller 39 on the latter is held in contact with the cam surface 38 by the spring 401, the member 40 will move inward and outward along the arm 42 according to the path defined by the cam 38. 70

The length of the can-moving arms 31 is such that they extend beyond and clear the outer edge of the table 28, the outer ends of the arms having upwardly extending portions 314 projecting a distance above the top 75 of the table 28 and portions 315 which extend radially inwardly above the surface of the table. The inclined blocks 316 and the resilient concave can-engaging members 317 are mounted on the forward sides of the portions 315. The members 317 are normally shaped so they are of a curvature of less diameter than the cans. The arms of the members 317 are opened slightly when the cans are pushed into the curved sockets formed 80 thereby, whereby the cans are firmly grasped so they will not turn in the pockets and to further prevent turning in the pockets, the inner concave surfaces of the members 317 are provided with transverse ribs 317' or otherwise roughened to produce a frictional holding face which contacts with the cans. The members 317 hold the cans outwardly 85 against the rim flange 283 and coöperate with said flange 283 on the table 28 to keep the 90 cans moving in a fixed path as the arms 31 are rotated. The inclined blocks 316 are arranged to engage the trip lever 44 which operates to release a can just as a can-engaging member 317 is in a proper position opposite 95 the can-feeding mechanism to receive it.

From Fig. 1 it will be seen that each revolution of the spindle 36 causes a can to be moved from the belt conveyer 43, across the bridge 431 and gap 432 onto the table 105 28 and into the concave can-engaging member 317 in position to receive the can. The belt 43 which conveys the cans C from the filling machine or other apparatus has guide rails 433, 433 extending along the top at 110 the sides thereof and the belt passes around a roller 434 which is journaled as close as practicable to the table 28. The intervening space is bridged by a plate 431 except for a narrow gap 432 through which the 115 upwardly extending portions 314 of the arms 31 pass.

The trip lever 44 is pivoted intermediate its ends on the support 441 and is yieldingly held in the position shown in Fig. 1. The 120 outer end of the lever 44 is connected by a chain or other flexible device 443 to one arm 451 of a stop dog 45 which arm 451 is connected by a chain 452 to the arm 461 of a second stop dog 46. The dogs 45 and 46 125 are pivoted intermediate their ends on the sleeve 37 and support 462 respectively and the arms 451 and 461 are held in a fixed position by the springs 453 and 463 respectively, connected to the supports 462 130

and 464 respectively. The springs 453 and 463 exert a tension on the chains 443 and 452 respectively, and serve to yieldingly hold the end 444 of the lever 44 in the path 5 of the tripping blocks 316. When the lever 44 is tripped, the dogs are rocked on their pivots and the arms 455 and 465 thereof are moved out of the path of the cans which they engage. The continuously 10 moving belt 43 and feed device 42, 40 then coöperate to move the can released by the arm 455 onto the table 28, whereas the can released by the dog 46 moves forward to be engaged by the arm 455, as the latter is 15 immediately restored by the spring 453 and the dog 46 is also returned to its initial position by the spring 463 while both springs by reason of their flexible connection with the lever 44 restore the latter to a position 20 in the path of the next arm 31.

When a can has been moved onto the table 28 at the feeding station A, the next step of the conveying arm 31 moves the can to station B where the cans are trued 25 up and where the caps are initially secured in place.

Referring to Fig. 2^a each cap *a* comprises a disk-like member having, if desired, a depressed central portion *b* and a 30 flat peripheral rim portion *c* provided at intervals of 120° with integral radial tongues *t*. The exterior surface of the peripheral wall *w* of the depressed portion has a continuous groove *g* therein which contains solder, albumen or some other suitable sealing or securing medium. The tongues are designed to be doubled on themselves and tucked beneath the usual outer flange on a can, the ends of the tongues being left 35 projecting from beneath the flange to provide means whereby the cover may be easily detached from the can.

As will be seen from Figs. 1 and 2 the can comes to rest at station B directly beneath a substantially cylindrical magazine 50 of slightly greater diameter than the can caps and provided with three slots 501 extending longitudinally thereof to receive the tongues *t* on the caps, which also serves 40 to guide the caps so that they will discharge from the magazine with the tongues thereof at the proper points to be operated on by the tongue folding or tucking mechanism. There are usually as many tongue tucking 45 devices as there are tongues on the cover and in the present instance there are three, but since they are alike only one of them will be described.

The stack of caps is supported in nested 50 relation at a point above the bottom of the magazine 50 by the members 51 which operate to slightly separate the bottom cap from the stack.

Three similar members 51 are provided, 55 each of which is pivoted at 511 in a recess

502 in the wall of the magazine 50 and has a rounded nose 512 at its lower end projecting inside the magazine to engage under the stack of cans to support the same. The nose 512 is normally held in its projecting 70 position by a spring 513 which allows said nose to be depressed into the recess 502 when a cap is removed from the bottom of the stack. Above its pivot the member 51 has two projections 514 and 515 adapted to 75 project into the magazine when the nose 512 is depressed. The projections 514 hold up the stack of caps till the noses 512 return to their normal position when the projections 514 will release the stack and let it down onto the noses 512. The projections 515 enter between the second and third caps from the bottom to separate them, should 80 they become wedged together.

The device for taking the caps off the 85 bottom of the stack and placing and holding them on the mouth of the can comprises two similar plates 52, 52 both of which are pivoted on the pin 53 which is mounted near its opposite ends in the parallel brackets 90 54, 54. The pair of brackets 54, 54 is rigidly secured to the magazine 50 at opposite sides of each of the slots 501 therein and at the lower end thereof. Each pair of plates 52, 52 moves together, and the plates of each 95 pair are spaced apart so that they will allow the tongues of the caps to pass between them and so that the beak 521 of the plates will engage the peripheral flat portion of the cap on opposite sides of the tongue. The 100 beak 521 of each plate is pivotally mounted at 522 on the forward end of the plate and the rear edge thereof fits in a recess, a spring 523 serving to normally hold the beak 521 in its extended position, but permitting it to yield when the plate passes the bottom of the stack on its return upward to normal position of the cap removing devices. Each plate 52 has an outwardly extending arm 525, and the arms 525 110 of each pair of plates are connected together at their outer ends by a pin 526 whereby the plates 52, 52 of each pair may be rocked in unison on the pivot pin 53. A link 527 is connected at each end of the pin 526 outside the arm 525 and extends upwardly where it is pivotally connected to a bracket 551 extending outwardly from a sleeve 55 115 slidable along the outer surface of the magazine 50, said sleeve being provided with the 120 enlargement 552 adjacent the slots 501 so that the tongues on the caps may freely pass therethrough.

The mechanism for reciprocating the sleeve 55 along the magazine and thereby 125 operating the cap removers comprises the two cams 56 mounted to rotate with the shafts 57 and 58 journaled in the bearings 571 and 581 respectively on opposite sides of the magazine. The sleeve 55 is connected 130

to the two cams by suitable rods 561, 561, which have anti-friction rollers at their ends to fit suitable cam grooves in the cams 56.

The shaft 57 derives its rotation from a central vertical shaft 59 through the gears 572 and 573, and it rotates, at the same speed as the shaft 59. The shaft 59 is journaled in the frame 69, standard 29 and bearing 30 and has a sprocket wheel 591 on a reduced lower end 592 thereof. A chain 593 transmits power from the sprocket 594 fixed on the main drive shaft 34 to the sprocket 591 fixed on the shaft 59, and the sprockets being of the same size the shafts will rotate 10 at the same speed.

The sprocket 595 on the shaft 59 and below the sprocket 591 drives a chain 596 which drives a sprocket 611 fixed on the shaft 61. The shaft 61 is journaled in suitable bearings 612 on the upright 613 and leg 20 26 and transmits power to the shaft 58 through the gears 582 and 583.

When the cover has been removed from the bottom of the stack by the remover 25 devices comprising the plates 52, 52, the latter at all three points around the periphery of the can assume the position shown in Figs. 2, 6, 7, and 8, and the devices which tuck or double the tongues beneath the 30 flanges on the cans begin operating.

The folding and tucking means comprises the members 62 and 63 which are pivotally mounted on the pins 621 and 631, respectively, which are carried between the plates 52, 52. The tuckers 62 and 63 are 35 held in their initial or normal position as indicated in Figs. 3 and 6, by the torsion springs 622 and 632 respectively. Those springs 622 and 632 surround the pins 621 and 631 and serve to restore the members 40 62 and 63 to their normal positions after the tucking operation.

The initial position of the devices after the cover has been removed from the magazine and placed on the can is as indicated 45 in Fig. 6. A downwardly moving pair of rollers 641, 641 carried by a sleeve 64 engage the tucker member 62, the tucking finger 623 of which engages the top surface of the block 63. The members 62 and 50 63 bend the tongue *t* at *t'* and bend the end thereof down against the top surface of an anvil 65, see Fig. 7. A further downward movement of the roller 641 does not alter 55 the position of the block 63 but the member 62 will be swung still further on its pivot and the tucking part 623 thereof will bend the tongue *t* at *t''* thus doubling a part 60 of the tongue upon itself beneath the flange on the can and leaving a part projecting from beneath the flange for a detaching grip.

The sleeve 64 which imparts the motion to the rollers 641 carried thereby is located 65 below the sleeve 55 and also slides along the

outside of the magazine 50. It is reciprocated by means of two suitable cams 66 carried by the shafts 57 and 58 on opposite sides of the magazine. Suitable rods 661 provided with antifriction rollers connect 70 the sleeve 64 to the cams 66 which are provided with suitable grooves in the face to receive said rollers, as is the case with the cams 56. The sleeves 55 and 64 simultaneously move in opposite directions and therefore will not interfere.

The shaping molds and anvils 65 and 651 which fit beneath the flange on the can are each semi-circular in shape to conform when closed to the shape of the outside of the can, 80

serving to true up the can body and they are each provided with shallow recesses to correspond to the width of the members 62 and 63 and located at the points where the tongues on the cans are positioned. The shaping an- 85

vils 65 and 651 are horizontally slidable on the brackets or supports 652, 652, fixed to rigid parts of the machine. The rotary cams 671 and 67 are fixed on the shafts 61 and 672, respectively, the latter being geared 90 to the shaft 57. Said cams 67 and 671 have grooves which receive the antifriction devices on the stems 673, 673 of the anvils 65, 651 and move the latter horizontally into closed and open position as the cans arrive 95 and depart, the cams being designed and timed so as to leave the space between the brackets 652 open when the cans are moving to and from the cap receiving station.

The cams 56, 56 and 66, 66 are of course designed and timed to operate when a can and the anvils are in cap-receiving position, and by means of the devices which those cams control the caps are secured to the flanges at three points and are prepared for the 105 seaming operation. But before the cans are moved on to the seaming station S they are brought to rest at an inspection station I where they may be examined for an instant, after which they move onward to the seaming station S.

The can being at rest at the seaming station and having its flange still extending out normal to the body and having its cover temporarily secured thereto, is engaged by 115 the semi-cylindrical shaping members 68 and 681 which are complementary and provide a mold to shape the can for the operation thereon of the seaming devices.

The mold members 68 and 681 move horizontally into position to engage the outer surface of the can body and then along the latter upwardly so that its upper edge will be positioned so as to engage the under side of the can flange when the seaming opera- 125 tion begins.

The horizontal movement of the mold members 68 and 681 is effected simultaneously by means of two cams 69 and 691 which are mounted to rotate with the verti- 130

- cal shafts 692 and 693. The shafts 692 and 693 are mounted in suitable bearings and are geared at their upper ends to the shaft 70 which extends horizontally above the 5 seaming station, being journaled in the frame members 71 and 72 and geared to the central shaft 59 by the gears 73 and 74, the latter being fixed on the upper end of a reduced section of the shaft 59.
- 10 The means for supporting and operating the halves of the mold are similar and therefore the means associated with the member 68 only will be described. Referring to Figs. 9, 10 and 11, the mold 68 is provided on its 15 convex side with two flanges 75, 75, which are each engaged on their under sides by a series of lugs 761 which are formed integral with the curved plate 76. Each curved plate 76 has a rearwardly projecting lug 762 which 20 is provided with a roller 763 that fits a groove 694 in the cam 69. Because of this positive connection the rotation of the cam 69 causes the inward and outward movement of the plate 76. Near the upper and lower 25 edges of the convex side of the plate 76 there are attached a series of lazy-tongs devices 77 which have their inner ends rigidly mounted on the concave inner side of a curved supporting member 78 carried by 30 the table 28. The curved supporting member 78 has an opening extending therethrough to allow the free movement of the cam 69, and said supporting member is braced at the rear by the part 781.
- 35 The vertical movement of the mold section 68 is obtained from a cam 79 which is keyed to and slidable along the sleeve 791, which latter is rotatable with the shaft 792 geared to the shaft 692 by the gears 793. The 40 shaft 792 is supported horizontally in suitable bearings and has a groove 794 to retain the rollers at the end of the rod 80 which is supported vertically and works in guide openings in the central lugs 761 on 45 the plate 76. The rod 80 is welded or rigidly secured to the flange 75.
- The cams 69 and 79 are so constructed and timed that the cam 69 first moves the mold section horizontally toward and against the 50 can body. The cam 79 during this step of the operation slides along the sleeve 791, the cam grooves 794 and 824 being so shaped as to produce a dwell for the rods 80 and 823 and hold them against upward movement, the cam 79 turning but imparting no motion to rods 80 and 823. When the mold 55 sections are up against the can body, the rods 80 and 823 are lifted by the cam 79 into the position, as shown in Fig. 10, this movement taking place in a relatively brief interval of time to give sufficient time for the seaming operation. At the upward end of the stroke there is a slight dwell in the cam 60 while the seaming devices operate when the 65 movement of the parts reverses to restore the parts to their initial position for the succeeding can.
- The upper edge of the mold sections 68 and 681 are each provided with a series of notches 81 in which the lower corrugating 70 fingers 82 are pivoted. Each of the corrugating devices 82 has a rod 821 connected to the under side thereof intermediate its ends. The rods 821 have their lower ends pivotally connected to a split ring 821' which 75 is raised and lowered at the proper times by a rod 823. The rod 823 is guided vertically by a hole in the lower of the flanges 75 and has its lower end retained by a cam groove 824 in the cam 79, whereby it is reciprocated. 80
- When the mold sections 68, 681 are in raised position, the radial fingers 82 engage the under side of the flange on the can, as shown in Fig. 13, the finger 82 shown in that figure being somewhat longer 85 than other fingers and being designed to fit the tab which has been tucked under the flange on the can, as previously described. At the same time that the fingers 82 are in engagement with the under side of the flange 90 on the can, the peripheral edge portion of the upper side of the cover is engaged by the upper radial corrugating fingers 83, at points in different radial planes from the lower corrugating fingers as will be clear 95 from Figs. 17, 18 and 19.
- The fingers 83 are pivoted at 831 in notches on the flange 832 having the top 833 which is rigidly secured or welded to a head 84 slidable in a central opening in the circular member 85. Motion is imparted to the head 84 by a rod 841 connected to a cam 842 mounted to rotate with the shaft 70. The member 85 is connected by the rods 851, 851 to the cams 852, 852, which are fixed 100 to rotate with the shaft 70 and reciprocate the member 85 up and down in the annular bearing 86 which is connected at its opposite sides to the frame members 71 and 72 by means of the brackets 861, 861. An annular 105 plate 87 is connected to the lower side of the member 85 and has an inwardly extending flange 871 spaced from the bottom face of the member 85, whereby a circular recess 872 is formed to receive the outer ends of 110 the fingers 83 which carry antifriction rollers and move radially into and out of the recess 872. It will therefore be seen that the outer ends of the fingers 83 are freely movable a certain amount radially. 115
- In order to force the sealing material out of the groove in the outer side of the depressed portion of the cap and also to hold the latter on the body during the seaming operation, a center pad 88 is provided which 120 has a peripheral wall 881 the same diameter as the inner diameter of the depression in the cap, and may be slightly tapering so as to gradually press out the interior bead which corresponds to the exterior groove in 130

the cap, thereby expelling the sealing material from said groove into the space between the cap and can wall. The inside of the bottom wall of the pad 88 has a stem 882 at the center thereof passing through an opening in the top 833, and provided with an enlargement 883 at the upper end thereof to hold the pad on the head 84 with which it moves. A spring 884 surrounds the stem 882 and is disposed between the top part 833 and the bottom of the pad 88, whereby the pad is yieldingly held in extended position, as shown in Fig. 9. The center pad 88 carries an annular gas pipe 89 provided with suitable nozzles 891 which impinge against the wall 881 of the pad so as to heat the pad whereby the sealing or soldering material will flow into place more readily. Gas may be led to the pipe 89 by any suitable means as for example, by a flexible tube passing through openings in the top 833 and the member 854.

The seaming operation will now be described. The moment the can reaches the seaming station S the seaming mechanism is in the position, as shown in Fig. 9, whereupon the cams, which are continuously rotating operate and move the shaping mold and the fingers 82 thereon inwardly and upwardly to the position shown in Fig. 10. Simultaneously, the upper corrugating or seaming fingers are moved into the position shown in Fig. 10, the center pad 88 being lower than the two part seaming head, will reach the head of the can first and may yield a slight amount to accommodate cans of slightly different heights and the difference in the stroke of the seaming head. By the correct arrangement of cans the part 84 has reached and holds the lower limit of its movement when it and the center pad is in position, as shown in Fig. 10, the center pad having pressed the sealing material from the groove in the cap and flattened out the bead.

The annular seaming part 85 continues to move downwardly and thereby carries the outer ends of the fingers 83 down with it, the fingers 82 receding at the same speed downwardly as the fingers 83 move down and finally near the end of the downward stroke, receding very rapidly, so as to move the lower corrugating devices out of the way to let the upper fingers 83 finish the corrugating operation. The successive positions of the corrugating and simultaneous bending operation which seams the cap to the can, is shown in detail in Figs. 13 to 19 inclusive. The peripheral edge portion of the cap and the flange on the can being flat, as shown in Figs. 13 and 17, and the upper and lower corrugating and bending fingers being on the top and bottom sides of the edge of the cap and flange respectively, the lower fingers are rotated down-

wardly a distance on their pivots by the cam 79, and the head 84 presses against the upper end of the can while the head 85 having the hollow part 854 moves the outer ends of the fingers 83 down about their pivots 831 to the position approximately as shown in Fig. 14 and at which point the cams 79 withdraw the mold members 68, 681 and fingers 82. As the downward movement of the head 85 continues, the fingers 83 will push the outer ends of the flange and cap downward and then inward toward the wall of the tubular body, as shown in Figs. 15 and 16, and until said flange and peripheral edge of the cover are disposed alongside the body. It will be understood that the fingers 83 shown in Figs. 13 to 16 are the special fingers located at the points where the tongues on the cap are positioned and are somewhat longer than the other fingers, such as the one shown at the right side of the can body in Fig. 10, whereby the longer fingers simultaneously corrugate the tongues and flanges.

Near its pivotal connection 831, each of the upper row of fingers 83 has a concave recess 836 on its face that engages the surface of the cap. The concave recesses in the fingers are arranged in a circular row and are designed to simultaneously form a resilient bead *r* on the can body and a similar bead in the cap which provides an inside groove in the cap, the bead on the body fitting into the groove on the inside of the lid. It will be understood that the resilient bead thus provided on the cover and formed during the corrugating or seaming operation will more effectively hold the cover on the can since the cover has a part engaging beneath the shoulder formed by the bead. Furthermore, the interfitting bead and groove provide additional sealing surfaces between the cap and body.

The moment the peripheral edge of the cap and the flange are corrugated and bent down to the position shown in Fig. 14, the cam 842 and the cams 852, 852 raise the inner and outer heads 84 and 85, and the cams 79, 79 lower the molds 68, 681 and move them apart, the position of the parts then being that shown in Fig. 9. Then the can propelling means operates to move the seamed can forward one step to the inspection station I' and the following pusher arm moves a can to the seaming station S from the inspection station I. The next step forward moves the can to the removal station R where it is removed by a rotating arm 90. The arm 90 is mounted on the spindle 901 on the platform 27 and is rotated by a sprocket chain 902 which is rotated by the shaft 34. The arm 90 rotates so that it will move in behind the can and above the curved member 317, pushing the 130

can along the guide rails 91, 91 and onto the conveyer 92 by means of which the cans are carried to the labelers or packers.

What I claim is:

5. 1. Apparatus for attaching a cover part to a tubular body part which comprises the combination of, means for assembling a body part and a cover part, and means for corrugating the two parts at their edges and bending the same so that the edges will define an edge of a lesser length than they had before the corrugating and bending operations. 70
10. 2. Apparatus for securing an initially substantially flat cover part to a flanged tubular body which comprises the combination of means for assembling a body part and a cover part, means for corrugating the two parts at their edges and bending the same so that the edges will define an edge of a length less than the length of the edges before the corrugating and bending operations, and means for moving such united body and cover parts away from such corrugating and bending means. 80
15. 3. Apparatus for attaching a cover part to a tubular body part which comprises the combination of, means for assembling a cover part upon a body part, and means for radially corrugating the peripheral edge of the cover part and the edge of a portion of the body part, and simultaneously bending said corrugated parts inwardly toward the axis of said body part, whereby the corrugated edges will be of a length less than the length of the parts before corrugating and bending them. 85
20. 4. Apparatus for attaching a cover part to a tubular body part having an outer flange which comprises the combination of, means for superposing the cover part on the flange of the body part, means for corrugating the two parts together and simultaneously bending the corrugated parts so that the edges thereof will define a peripheral edge of less length than the parts had before the corrugating operation. 90
25. 5. In apparatus for attaching a cover blank to a tubular body blank having a flange the combination of, means for supporting a tubular body, means for feeding a cover blank to the body blank, and means, including pivoted fingers for corrugating and simultaneously bending the cover blank and flange of the body blank alongside the tubular body blank. 95
30. 6. In apparatus for securing a cover to a container, the combination with means for fitting the parts together with their edges contiguous, of means for corrugating the edges and bending said edges so that they define edges of less length than at the beginning of the corrugating and bending operations. 100
35. 7. In apparatus for securing a disk-like part to a flanged tubular part, the combination of, means for superposing one of the parts on the other so that the edge of the flange and peripheral edge of the circular part are contiguous, means for radially corrugating said contiguous edges, and simultaneously bending the corrugated portions as the length of the peripheral edges decrease due to the corrugating operation. 105
40. 8. In a machine of the class described, the combination with a stationary support for containers and the like, of a traveling member for moving a container along said support, and mechanism for feeding containers to said support comprising means for moving a series of containers toward said support, a stop in the path of such series of containers, means operable by said traveling member for actuating said stop to release a container for movement of the same onto said support, and means for moving a released container onto said support into position to be engaged by said traveling member. 110
45. 9. In a machine of the class described, the combination of a can support, a can moving member, a can feeding mechanism comprising a rotating arm capable of moving a can onto said support and a stop normally in the path of cans to be fed onto said support, and means whereby said can moving member actuates said stop to release a can for movement onto said support by said rotating arm. 115
50. 10. The combination with an article carrying means or support, of means for feeding articles to such support comprising a rotatable arm having an extensible portion, and means for actuating such extensible portion to increase and decrease the effective length of said arm. 120
55. 11. The combination with an article carrying means or support, of means for feeding articles to such support comprising a rotatable arm having an extensible portion, and means comprising a cam co-operating with such extensible portion to move the same along the arm to increase or decrease the effective length of said arm. 125
60. 12. In a machine of the class described, the combination of an intermittently operating can moving member, and mechanism for feeding cans to said member, said mechanism comprising a can propelling device, two releasable stops, normally in position to stop two successive cans fed by said propelling device, a compound arm adapted to move cans to said intermittently operating member, a cam associated with said arm, and a trip operable by said intermittently operating member to actuate said stops to release the cans held thereby. 130
65. 13. In a machine of the class described, the combination of a hollow stationary post, a table carried by said post and having an operating position thereon, a rotatable mem-

ber below said table, means operable by said rotatable member for moving containers along the upper side of said table to and from said position, mechanism above said table for operating upon a container at said position, a rotating shaft disposed in said post and connected to said mechanism to operate the same, and means connected to the lower end of said shaft below said table and rotatable member for driving said shaft.

14. In a machine of the class described, the combination of a stationary table having an operating position thereon, a rotating shaft extending above and below said table, means below said table for driving said shaft, means comprising a member rotatable independently of said shaft and around the axis of said shaft below the table, for moving containers along the upper surface of said table to and from said operating position, means for operating upon the containers at said operating position, and means for driving such operating means from a part of the shaft above the table.

25. In an apparatus for closing tubular bodies the combination of a central post, a stationary table supported by said post, a plurality of operating stations arranged concentrically about said post, and rotatable means having portions extending from beneath said table and over the same, and capable of being operated from beneath said table for moving tubular bodies to and from said operating stations.

35. In an apparatus for closing containers, the combination of a post, a stationary table supported by said post, an operating station on said table, a rotating member supported by said post and disposed beneath said stationary table, and means comprising arms connected at their outer ends to said rotating member and operable by the latter to move containers along said table to and from said operating station.

45. In a machine of the class described, the combination of a platform, a stationary hollow post on the upper side of the platform, a table supported by said post and having an operating position on the upper side thereof, means for moving containers along the upper side of said table to and from said position, such moving means comprising a member rotatable around the axis of said post and disposed between said platform and said table, mechanism above said table for operating upon a container at said position, a shaft mounted in said hollow post and projecting above the latter and below said platform, means connected to the lower end of said shaft for operating the same, and means for operatively connecting said mechanism to the part of the shaft above said post.

55. In a machine of the class described, the combination of a support for container

bodies, a stack holder for container covers above said support, and pivoted means movable radially of said stack holder for removing a cover from said stack in a direction axially of the stack holder.

70 19. In an apparatus for closing flanged tubular bodies, the combination of a support for a flanged tubular body, a shaping mold to true up said body, and means for securing a head to said tubular body, said 75 shaping mold engaging said body and the flange thereon while the cover is being secured.

20. In a device of the class described, the combination of a magazine for holding 80 a stack of covers, means for removing a cover from said stack, and means on said removing means for securing a cover to a body part, said securing means being movable in relation to said removing means.

85 21. In a machine of the class described, the combination of a support for a container body, of means for attaching to said body a cover part having a tongue projecting outside the margin of said cover proper; 90 said means being adapted and arranged to bend said tongue at a point between the cover proper and the outer end of the tongue.

22. In a machine of the class described, the combination of a tubular holder for a 95 stack of covers or the like, of pivoted means for supporting said stack in said holder, and pivoted means swingable in a direction longitudinally of the axis of said holder and into said holder to remove the bottom 100 cover from said stack.

23. In an apparatus of the class described, the combination of a magazine for closures, a body support below the magazine and pivoted means movable radially of a body 105 on said support for removing a closure from the lower end of said magazine, placing it on a body and securing it thereto.

24. In an apparatus for feeding and applying a cover to a tubular body, the combination of a support for a tubular body, a magazine for holding covers, and pivoted means movable into and out of said magazine for removing a cover from the lower 110 end of said magazine and applying it to the 115 body.

25. In a machine of the class described, the combination of a container support, and seaming means for uniting a cover to a container on said support, said seaming means 120 comprising two cooperating annular series of means for corrugating contiguous portions of said container and cover to provide interfitting corrugations on the container and cover.

125 26. In a machine of the class described, the combination of a body support, means for engaging and shaping a body on said support, and independently movable pivoted means carried by such shaping means for 130

- operating on a body that is engaged by such shaping means.
27. In a machine of the class described, the combination of a body support, movable members for engaging and shaping a body on said support, and means for uniting a cover to said body, such uniting means comprising swingable means movable to and from operative position with such shaping members and also movable independently of the latter.
28. In a machine of the class described, the combination of a stationary support for a flanged body, means for engaging the body below its top flange to shape the body and its flange, and corrugating means capable of engaging said flange and a cap on the body and operative to secure said cap to the flange.
29. In a machine of the class described, the combination of a stationary support for a flanged body, means for engaging the body below its top flange to shape the body and its flange, and a series of pivoted members above the cap and a series of pivoted members below the flange cooperating with said upper series of members to seam the cap to the body.
30. In a machine of the class described, the combination of a body support, a body shaping mold, and seaming mechanism, said seaming mechanism comprising pivoted means mounted on said shaping mold.
31. In a machine of the class described, the combination of a body support, a body shaping mold, and seaming mechanism pivotally supported thereon, said shaping mold being in operative position during the seaming operation.
32. In a machine of the class described, the combination of a body support, a substantially cylindrical body shaping mold, and means whereby said cylindrical mold is moved upwardly and downwardly relatively to a body on said support.
33. In a machine of the class described, the combination of a body support, a two-part body shaping mold, and means for moving both parts of said shaping mold horizontally and vertically relatively to a body on said support.
34. In a machine of the class described, the combination of a body support, a body shaping mold, seaming mechanism comprising pivoted upper and lower members, said lower members being mounted on said shaping mold, and means for operating the shaping mold and the seaming members mounted thereon.
35. In a machine of the class described, the combination of a body support, means for seaming to a body on said support a cap having a depressed portion, said depressed portion fitting into the mouth of said body, the peripheral wall of said depressed por-
- tion having a groove for a sealing substance, said groove providing a corresponding bead on the inside of said depressed portion, and a center pad having a tapering part fitting said depressed portion and adapted to engage said bead to force sealing substance from said outer groove.
36. In a machine of the class described, the combination of, a support for a tubular body, means for placing a cover part upon one end of said body, and mechanism for corrugating together the contiguous peripheral edges of said body and the cover thereon and for bending such edges inwardly toward the axis of said body.
37. In a machine of the class described, the combination of a support for an externally flanged tubular body, means for placing a cover upon said body with the peripheral edge of such cover adjacent to the peripheral edge of such flange on the body, and mechanism for corrugating transversely of such flange and the adjacent edge of the cover to produce interfitting corrugations in said flange and cover throughout the extent thereof and for bending such corrugated portions inwardly around said body.
38. The combination with a horizontal support for container bodies and the like, of a vertical stack holder for container covers above said support, and mechanism comprising vertically swingable pivoted means for removing a cover from the lower end of said stack in a direction axially of said stack holder.
39. In a machine of the class described, the combination of a support for a tubular body, and mechanism comprising a circular series of members movable radially of said body for forming a bead or shoulder on said body and for securing a closure to said body beneath said bead.
40. In a machine of the class described, the combination of a support for a tubular body, and pivoted members movable radially of said body for forming a bead or shoulder on said body and for securing a closure beneath said bead or shoulder.
41. In a machine of the class described, the combination of a support for a body, and mechanism for forming a bead on said body and for corrugating and bending a portion of a closure beneath said bead.
42. In a machine of the class described, the combination of a support for a tubular body, and mechanism for forming a bead on a body and for simultaneously transversely corrugating and bending the edge of a cap beneath said bead.
43. In a machine of the class described, the combination of a support for a body, and mechanism for seaming a cap to said body comprising upper and lower independently movable pivoted members.
44. In a machine of the class described, the

combination of a support for a tubular body having a flange, and mechanism for securing a cap to said body, said cap initially having a substantially flat peripheral portion, said mechanism comprising means for transversely corrugating and bending down said flange of the body and flat portion of the cap.

45. In a machine of the class described, 10 the combination of support for a body having a cover-engaging shoulder, a magazine for cover blanks having flat peripheral portions and radial tongue means projecting outwardly from said peripheral portions, 15 means for feeding said blanks one at a time to bodies on said support, and mechanism for corrugating and bending the flat peripheral portion and a part of the tongue means of a cover blank so that its peripheral 20 edge projects under the cover-engaging shoulder and leaving part of said tongue means accessible, whereby the cover blank is detachably connected to the said body.

46. In a machine of the class described, 25 the combination of a can support, means for seaming to said can a cap having a depressed portion within its periphery, said depressed portion fitting into the mouth of a can, the can-engaging wall of said depressed 30 portion having a recess for a sealing substance, said recess providing a corresponding projection on the inside of said depressed portion, and a device having a part adapted to enter the inside of said depressed 35 portion and arranged for pressing against said projection so as to force the sealing substance from said recess into the space between the cap and the wall of the can.

47. In a machine for applying a cover to 40 the end of a tubular body, said cover having an outwardly facing recess containing seaming or sealing substance, the combination with means for positioning said cover in the end of said body so that said recess therein 45 shall face and be disposed close to the inner surface or wall of said tubular body, of means for applying pressure or heat or both to said cover to expel seaming or sealing substance from said recess into the space 50 between the adjoining parts of the body and cover.

48. In a machine of the class described, the combination with a support for tubular bodies, of means for securing a cover to a body on said support comprising a series of radial 55 corrugating members for engaging the cover part, a series of radial corrugating members for engaging the body, and means for operating said corrugating members to cause them to cooperate to produce interfitting 60 corrugations in said cover part and body part.

49. In a machine of the class described, the combination with a support for tubular bodies, of means for securing a cover to a body on said support comprising a series of radial corrugating members for engaging the cover part, a series of radial corrugating members for engaging a flange on said body, and means for operating said members to 70 cause them to cooperate to produce interfitting corrugations in said flange and cover and simultaneously to bend the interfitting corrugated parts toward the axis of said tubular body.

50. In a machine for applying cover parts to tubular body parts, one of said parts having recess means containing a seaming or sealing substance, the combination of means for positioning a cover part and a body 80 part so that the portion of the part carrying the seaming or sealing substance shall be disposed close to and opposite a wall of the other part, and means for applying pressure and heat to expel substance from such 85 recess means into the space between the opposed walls of such parts.

51. In a machine for applying, to a tubular body part, a cover part having a groove containing seaming or sealing substance, 90 the combination of means for positioning said cover part upon said body part so that said groove and the substance therein shall face and be disposed close to a wall of the body part, and means for applying pressure 95 or heat or both to the cover part to expel seaming or sealing substance from said groove into the space between the contiguous portions of the body and cover parts.

In testimony whereof I affix my signature. 100

EUGENE L. GREENEWALD.
